CLAIM

The ornamental design for golf grip, as shown and described.

DESCRIPTION

FIG. 1 is a perspective view of a golf grip showing my new design;

FIG. 2 is a front view thereof;

FIG. 3 is a back view thereof;

FIG. 4 is a right side view thereof;

FIG. 5 is a left side view thereof;

FIG. 6 is a top plan view thereof;

FIG. 7 is a bottom view thereof;

FIG. 8 is a detailed view of area 8 of the golf grip as illustrated in FIG. 1;

FIG. 9 is a detailed view of area 9 of the golf grip as illustrated in FIG. 2;

FIG. 10 is a detailed view of area 10 of the golf grip as illustrated in FIG. 3;

FIG. 11 is a detailed view of area 11 of the golf grip as illustrated in FIG. 4; and,

FIG. 12 is a detailed view of area 12 of the golf grip as illustrated in FIG. 5.

The broken lines show portions of the golf grip and the bounds of the enlarged views and form no part of the claimed design. The paired dot-dash lines show boundaries of the claimed design and form no part thereof. The area between paired dot-dash lines forms no part of the claimed design.

1 Claim, 5 Drawing Sheets
